UNITED STATES PATENT OFFICE.

ORANGE O. OZIAS, OF DAYTON, OHIO, ASSIGNOR TO THE COMPUTING SCALE COMPANY, OF OHIO.

DESIGN FOR A FRAME FOR SCALES.

SPECIFICATION forming part of Design No. 31,923, dated December 5, 1899.

Application filed October 30, 1899. Serial No. 735,327. Term of patent 14 years.

To all whom it may concern:

Be it known that I, ORANGE O. OZIAS, a citizen of the United States, residing in Dayton, in the county of Montgomery and State of Ohio, have produced a new and original Design for a Frame for Scales, of which the following is a specification, reference being had to the accompanying drawings, forming part thereof, in which like numerals refer to like parts.

In the drawings, Figure 1 represents a plan view of a frame for a scale embodying my invention and design, and Fig. 2 is a sectional elevation view thereof on line X X of Fig. 1. The leading or essential feature of my design for a frame for a scale consists of a circular vertically-extending member having

an opening through its top and an extension on one side thereof.

In said drawings, 10 represents said circular vertically-extending member, 11 represents the opening through the top thereof, and 12 represents said extension on one side thereof.

What I claim is—

The design for a frame for a scale, substantially as shown and described.

In witness whereof I have hereunto set my hand this 30th day of September, 1899.

ORANGE O. OZIAS.

Witnesses:

CHARLES W. JAMES,
IRA C. KOEHNE.
